UNITED STATES PATENT OFFICE.

DANIEL D. WELLS, OF ALBUQUERQUE, NEW MEXICO.

WORKHOLDER FOR MACHINE TOOL BEDS.

Application filed May 29, 1926. Serial No. 112,581.

My invention relates to vises or clamps for holding work upon the bed of planing, milling or similar machines, and the object is to provide a simple and efficient device where-
5 by the work will be firmly held upon the bed in position to be acted upon by the knives, planers or other tools of the machine. The invention seeks to provide a compact mech-
anism which may be easily adjusted to the
10 work and will effectually resist lateral strain so that the work will be maintained in the position in which it is set. The invention is illustrated in the accompanying drawings and will be hereinafter fully set forth.

15 In the drawings:

Figure 1 is a sectional elevation of one embodiment of the invention;

Fig. 2 is an end elevation of one assembly of the vise;

20 Fig. 3 is a detail perspective view of a fulcrum member which is employed in the embodiment of the invention shown in Fig. 1;

Fig. 4 is a sectional elevation of a second embodiment of the invention;

25 Fig. 5 is a detail perspective view of the locking member.

In the drawings, the reference numeral 1 indicates a portion of the bed of a planing or similar machine and 2 designates a bar which is to be clamped to the bed plate for milling, planing, trimming or other operation. The bed plate is provided with longitudinal inverted T-shaped slots or 35 grooves 3 extending its entire length at opposite sides of the position in which the work is to be placed as is the common practice.

The vise of my invention includes a jaw 4 which is preferably a bar of rectangular 40 cross section having its forward face 5 at a right angle to its bottom 6, the jaw being adapted to rest upon the bed plate and the forward face being presented to the work. A jaw is disposed at each side of the work 45 and means are provided to lock the jaw in a set position upon the bed plate. In the upper edge of each jaw is a series of locking teeth 7 which are preferably of the same form as ordinarily given ratchet teeth with 50 their points directed away from the work, and in the forward end of each jaw is a socket 8 which is inclined downwardly and forwardly, as clearly shown. Spanning each jaw is an anchoring body or member 9 which 55 is substantially an inverted U-shaped structure through which the jaw extends and with-

in which, over the jaw, is a locking member 10, said locking member being provided on its under face with teeth 11 mating and adapted to engage with the teeth 7 of the 60 jaw, as shown and as will be understood. In the rear end of the locking member 10 is a recess or socket 12 which is semi-spherical in form and is adapted to receive the ball or sphere 13 at the forward end of an adjusting screw 14 which is threaded through the head or bridge member 15 of the anchoring body, the screw being provided at its rear extremity with a flat-sided head 16 to be engaged by a turning tool. In the drawings, I have shown the socket or seat 12 as entirely open at its outer or rear side, but it is to be understood that if so desired the edges of the seat may be compressed about the ball 13 so as to prevent separation of the 75 locking element from the adjusting screw. The anchoring body has its side members formed each with a vertical portion 17 and an upwardly and rearwardly inclined portion 18 extending from the upper end of the vertical portion, this inclination of the upper portion of the sides disposing the adjusting screw in a convenient position for adjusting the device and also bringing the upper portion of the anchoring body and the parts 80 cooperating therewith away from the work so that they will not interfere with the traveling planer, cutter or other working element of the machine. The vertical side portion 17 has its terminal formed into a substantially L-shaped foot 19 which is adapted to pass through the stem of the inverted T-shaped groove or slot 3 and cause its toe 85 90 95 100 105 20 to engage under the forward overhanging wall of the head of the groove. The rear side of this foot is inclined and reduced, as indicated at 21, whereby the foot may be readily entered into and engaged with the groove and a shoulder 22 is provided at the rear side of the foot at the junction of the same with the vertical side portion 17 adapted to rest upon the bed plate, as clearly shown. By slightly tilting the anchoring body, the foot 19 may be easily passed into the slot and the body then rocked to engage the toe 20 in anchoring position, as will be understood.

In the socket 8 is fitted a work-engaging pin consisting of a stem 23 of circular cross section to be inserted in the socket and a head or blade 24 which is preferably tapered forwardly to terminate in a compara-

tively thin edge 25. The head may be of conical formation, if preferred, so as to terminate in a point and with some classes of work the point is more desirable than the laterally expanded wedge-shaped head illustrated. It will be readily noted that the work-engaging point is directed downwardly and forwardly with respect to the jaw so that the holding force is exerted downwardly against the work and, consequently, the work will be firmly held down upon the bed of the machine.

It is desirable to elevate the forward end of the jaw so that, when pressure is applied thereto, the point 24 will be caused to operate downwardly against the work and thereby firmly secure the latter. For this purpose, a fulcrum member 26 is provided, said member consisting of a transverse arcuate plate or bridge 27, adapted to seat closely within a concave groove 28 formed across the under side of the jaw adjacent the front end thereof, and side plates or wings 29 rising from the ends of the bridge member 27 and preferably integral therewith. Each side plate or wing 29 is provided at its upper semi-circular edge with an inwardly projecting overhanging rib or flange 30 adapted to engage in a semi-circular groove 31 provided therefor in the side of the jaw, the fulcrum member being thereby held firmly to the jaw and separation of the parts being prevented. One side plate or wing 29 is equipped with a handle or lever member 32 whereby it may be adjusted.

In applying the device for use, the anchoring body is engaged with the slots or grooves 3 in the bed of the machine, as above described, and the jaw is inserted through the anchoring body so that it will rest upon the bed of the machine, the locking wedge 10 being withdrawn sufficiently to permit the ready insertion of the jaw. The work-engaging pins are fitted in the sockets 8 provided therefor and the fulcrum member is then rocked to the position shown in Fig. 1 so that the forward corners of the fulcrum member will rest upon the bed and the rear corners thereof will be lifted from the bed, the jaw being thus set in an inclined position with its front end elevated. The work-engaging pins are set against the opposite sides of the work and the jaws pushed forward so that the pins will be held to the work. The locking elements 10 are then set in engagement with the upper sides of the respective jaws and the adjusting screws 14 actuated to drive the locking members forwardly and downwardly, and this movement will, of course, be transmitted directly to the jaws so that they will be likewise driven forwardly toward the work and the locking pins embedded slightly in the sides of the work. After the pins have been caused to firmly engage the work, the fulcrum members are rocked rearwardly so

that the weight and force of the jaws will be exerted entirely upon the pins and through them on the work while the handle 32 of the fulcrum member will be moved out of the way of the traveling elements of the machine.

If the work or the bar to be trimmed is high or larger than may be securely held by the pins, as illustrated in Fig. 1, the form of jaw shown in Fig. 4 may be employed. In Fig. 4, the work 33 is indicated as being considerably larger than the work 2 shown in Fig. 1, and in such event the jaw 34 is provided with a vertical extension 35 at its front end so that, when the two jaws are brought together against the opposite sides of the work, there will be an extended vertical clamping surface brought against the work so that it will be firmly held, and it will often be sufficient to bring the faces of the jaws directly against the work, as shown. In the event, however, that it will be advantageous to have the work engaged by pins or points, sockets 36 may be provided in the jaws and in the vertical extensions 35 thereof so that a plurality of work-engaging points may be used. The form of the invention illustrated in Fig. 4 is adjusted and held upon the bed plate in the same manner as the first described form, the only difference being that the jaws rest flat upon the bed of the machine and are provided with the described vertical extensions.

While, as stated, the work-engaging pins may terminate in points, I prefer to employ the wedge-shaped heads illustrated in the drawings as I thus obtain a wide edge to engage the side of the work so that the clamping action will be spread over a somewhat greater area of the work and more effectually utilized. It is to be particularly noted that the reduced width of the foot on the anchoring body and the inclination of the rear side of the foot permits it to be easily engaged in the slot of the bed plate and it is not necessary to slide the vise the entire length of the bed after inserting the foot in the slot at one end thereof. The inclination of the work-engaging pins and of the adjusting screw causes the jaw to be held down firmly on the machine bed and secures the work firmly and accurately upon the same. In adjusting the work-engaging pins to the work, the outer or rear ends of the jaws serve as resistances to prevent movement of the jaws away from the work and, consequently, the pins will be slightly embedded in the sides of the work so that it will be firmly grasped and held to the bed of the machine. The device not only holds the work in upright position for the action of the tools but also holds it firmly directly upon the bed of the machine so that the work performed will be very accurate. When the device has been adjusted, the jaws cannot lift from the machine bed and thereby permit distortion of the work. It will be understood that a number of the vices will be employed

at various points in the length of the bar which is to be planed or trimmed and it is, therefore, possible to firmly clamp a bar which is of irregular form just as effectually 5 as a straight bar is clamped. The device is very light and easily handled and is not bolted to the machine bed but, when in place, is firmly anchored thereto. Inasmuch as it is not bolted to the machine bed, it may be 10 very easily and quickly removed and applied so that the proper number of vices may be employed and arranged in such position as may be desirable for the particular work to be done. It is also possible with this vise to 15 clamp thin strips upon the machine bed so that very thin stock may be operated upon.

Having thus described the invention, I claim:

1. A vise for holding work upon the bed 20 of a planing or similar machine comprising similar jaws adapted to rest upon a machine bed and movable thereon toward opposite sides of work resting on the machine bed, anchoring bodies each spanning a jaw and 25 constructed at its lower end to interlock with the machine bed, a locking member fitted within the respective anchoring body over the jaw, said member and the jaw being provided with mating interengaging locking 30 teeth and the said member being provided in its upper rear end with a concave seat, the teeth on the jaw being pointed away from the work-engaging end of the jaw and an adjusting screw mounted in the end of the anchoring body and provided at its front end 35 with a ball resting in the seat in the locking member.

2. A vise of the class described comprising a jaw adapted to rest upon a machine bed, a downwardly extending work-engaging element projecting from the front end of the jaw, an anchoring body spanning the jaw and constructed to interlock with the machine bed, means carried by the anchoring body to lock the jaw in a set position, a fulcrum member transversely bridging the under side of the jaw adjacent the front end thereof, and means whereby said member may be rocked longitudinally of the jaw between the jaw and the machine bed to support the front end of the jaw in elevated position while setting the work-engaging element to the work and then permit the lowering of the front end of the jaw whereby the work-engaging element will exert pressure downwardly as well as forwardly on the work. 40 45 50 55

3. A vise of the class described comprising a jaw adapted to rest upon a machine bed, the jaw being provided in its bottom adjacent its front end with a transverse concave groove and being provided in its sides with semi-circular grooves concentric with said transverse groove, a fulcrum member comprising a convex body seating in the concave groove in the bottom of the jaw, and side wings rising from the ends of the said body and provided at their upper ends with inwardly projecting ribs engaging in the semi-circular grooves in the sides of the jaw, and means for anchoring the jaw to the machine 60 65 70 bed and locking the jaw in a set position.

In testimony whereof I affix my signature.
